MEDICAMENT DROPPER

Donald Earl Dailey, Evansville, Ind., assignor to Mead
Johnson & Company, a corporation of Indiana

Application December 11, 1958, Serial No. 53,735

Term of patent 14 years

(Cl. D83—1)

Fig. 1 is a perspective view of a medicament dropper embodying my new design.

Fig. 2 is a side elevational view thereof.

Fig. 3 is an edge elevational view, i.e., one taken from either the right or the left in Fig. 2.

Fig. 4 is an end elevational view taken looking down on the dropper in Fig. 2.

Fig. 5 is an end elevational view taken looking upon the dropper in Fig. 2.

Fig. 6 is a sectional view taken along the line 6—6 of Fig. 2.

I claim:

The ornamental design for a medicament dropper, as shown.
